UNITED STATES PATENT OFFICE.

WILLIAM S. JACKSON, OF DETROIT, MICHIGAN.

STOVE.

No. 854,358.

Specification of Letters Patent.

Patented May 21, 1907.

Application filed December 29, 1906. Serial No. 350,021.

To all whom it may concern:

Be it known that I, WILLIAM S. JACKSON, a citizen of the United States of America, residing at Detroit, in the county of Wayne 5 and State of Michigan, have invented certain new and useful Improvements in Stoves, of which the following is a specification, reference being had therein to the accompanying drawings.

10 The invention relates to stoves, more particularly designed for the use of bituminous fuels, and the invention consists in the novel construction as hereinafter set forth.

In the drawings, Figure 1 is a vertical central section through the fire-pot of the stove; Fig. 2 is a horizontal section on line $x-x$, Fig. 1; Fig. 3 is a horizontal section on line $y-y$, Fig. 1.

15 A is the base, or ash-pit section of any suitable construction, and B is the fire-pot mounted thereon. This fire-pot is formed of a series of vertically extending hollow ribs or beads C spaced about its periphery, with intermediate solid wall sections D. The spaces 20

25 E, within the beads, form vertically extending flues which at their upper ends connect with lateral inwardly opening discharge apertures F, which are just beneath an annular flange G at the top of the fire-pot.

30 Near the lower ends of the flues E are outwardly opening air apertures H, and these are preferably formed in a damper-ring H' surrounding the fire-pot. This damper-ring is seated upon a bearing I on the fire-pot 35 beneath the beads C, and below the ring is a shoulder bearing J seated upon the top plate or ring K of the ash-pit section.

40 L are apertures in the ring K, forming downward extensions of the flues E opening into the ash-pit section.

45 With the construction as described, when the ring H' is adjusted with its apertures H in registration with the flues E air will be admitted into said flues, and discharged in a heated condition through the apertures F at the top of the fire-pot. This will cause the comparatively smokeless combustion of the distilled gases at the top of the bed of fuel, without increasing the combustion of 50 the solid fuel in said bed. It is to be observed that the air thus admitted does not enter the ash-pit or modify in any way the regulation of drafts for admitting air through the body of fuel. It merely consumes the 55 distilled gases and by adjusting the ring H', so as to vary the extent of the openings H,

the proper proportion of air to the gas may be obtained. Thus, when fresh fuel is introduced into the fire-pot the damper ring H' is preferably adjusted to admit a large quantity of air through the flues, and as the fuel becomes packed, and the distilled gases lessen, the ring H' may be adjusted to diminish the quantity of air.

55 The openings L, through the top K of the ash-pit section, are for the purpose of permitting the flues C to automatically clear themselves. These do not, however, affect the draft regulation, as the air entering the apertures H will be drawn upward through the flues C, and not downward. The inwardly extending flanges G at the top of the fire-pot serves to direct the hot air over the fuel, instead of permitting it to immediately rise.

75 My improved construction has a decided advantage over constructions in which the air is admitted through vertical slots in the inner wall of the fire-pot, for the reason that in such constructions a portion of the air will 80 pass through the body of fuel. With my construction, on the contrary, no portion of air entering the flues can find its way into the body of fuel. At the same time, the walls of the flues being formed integral with the fire- 85 pot, the air passing therethrough is heated, and without danger of burning out the flues.

75 What I claim as my invention is:

1. In a stove, a fire-pot having a series of vertically-extending flues communicating 90 with the interior of the pot at their upper ends and provided at their lower ends with externally-opening air inlet apertures, an ash-pit section beneath said fire-pot and downward-extensions of said flues below the externally-opening air inlet apertures forming 95 ash discharge passages into said ash pit.

2. In a stove, a fire-pot having a series of vertically-extending flues formed integral therewith, said flues communicating with the 100 interior of the pot at their upper ends and at their lower ends being provided with externally-opening air inlet apertures, an ash pit section beneath said fire-pot, downward extensions of said flues below said externally-opening air inlet apertures communicating 105 with said ash pit, and means for variably restricting said air inlet apertures.

3. In a stove, a fire-pot having a series of vertically extending flues formed integral 110 therewith, said flues communicating with the interior of the pot at their upper ends, and

having external openings near their lower ends, an apertured ring surrounding said pot and controlling said outward openings, an ash-pit section a cap in said ash-pit section 5 on which said pot is seated, said cap being apertured in alinement with said flues, for the purpose described.

4. In a stove, a fire-pot having a series of vertically extending flues formed integral therewith, said flues having externally opening apertures at their lower ends and internally opening apertures at their upper ends,

downward extensions of said flues, an ash-pit section with which said downward extensions communicate and an inwardly extending flange above said inwardly opening apertures for deflecting the air current through said flues inward. 15

In testimony whereof I affix my signature in presence of two witnesses.

WILLIAM S. JACKSON.
